UNITED STATES PATENT OFFICE.

JAMES M. BRENNAN, OF LOS ANGELES, CALIFORNIA.

ATTACHMENT FOR ACCELERATOR PEDALS.

Application filed April 28, 1924. Serial No. 709,550.

To all whom it may concern:

Be it known that I, JAMES M. BRENNAN, a citizen of the United States, and a resident of Los Angeles, in the county of Los Angeles and State of California, have invented certain new and useful Improvements in Attachments for Accelerator Pedals, of which the following is a specification.

My invention relates to and has for its purpose the provision of an attachment for accelerator pedals adapted to control or stabilize internal combustion engines, by means of which the operation of the pedal is steadied sufficiently to prevent the sudden, 10 jerky and unintentional opening and closing of the throttle when the car is traversing rough roads.

It is also a purpose of my invention to provide an accelerator pedal attachment of the above described character embodying a body wholly supported on the pedal and sufficiently rigid to allow the gradual application of foot pressure in depressing the pedal, but which, when subjected to sudden 20 pressure, collapses or yields to prevent the transmission of such pressure to the pedal.

I will describe only one form of attachment for accelerator pedals embodying my invention, and will then point out the novel 30 features thereof in claims.

In the accompanying drawings

Figure 1 is a view showing in side elevation a standard form of accelerator pedal having applied thereto one form of attachment embodying my invention;

Figure 2 is an enlarged sectional view of the attachment in applied position on the pedal;

Figure 3 is a top plan view of the attachment; and

Figure 4 is a bottom plan view.

Referring specifically to the drawings, in which similar reference characters refer to similar parts, my invention in its present embodiment comprises a supporting plate 15 which, in the present instance, is a metal disk provided with a peripheral annular flange 16. Soldered or otherwise secured to the under side of the disk 15 are intersecting strips 17 of such length as to provide fingers which are bendable to engage the head 18 of an accelerator pedal 19 and to thus securely hold the disk in firm position upon the head.

Supported on the plate 15 is a hollow resilient body 20, such body in the present

instance being formed of rubber and of semi-spherical formation. The body as a unit is confined upon the plate by means of a flange 16 engaging the edge of the body, as clearly shown in Figure 2, and this body is formed with a bleeding port 21 to allow the passage of air inwardly or outwardly of the body.

In practice, the attachment is applied to the head 18 of the pedal 19 by bending the finger 17 in the manner shown, whereby the body 20 is securely held in superimposed position with respect to the pedal head 18 for engagement by the foot of the operator. The body 20 is designed to withstand, without appreciably yielding or collapsing, foot pressure applied to the apex thereof, thereby providing a rigid connection between the foot and pedal so that the pressure of the foot will operate to depress the pedal. It will be understood that foot pressure applied to the apex of the body will tend, owing to the curved form of the body, to compress the side walls thereof and thus set up the necessary rigidity to prevent collapsing. The air confined within the body also aids in preventing the collapsing of the body owing to the restricted outlet 21. However, should foot pressure be suddenly applied to the body, that is, pressure at a rate appreciably exceeding the downward movement of the pedal, the body will yield to such sudden pressure and thereby prevent its transmission to the pedal 18. It will thus be seen that this depressing movement will be ineffective to depress the pedal.

From the foregoing operation it will be manifest that in practice the body 20 provides a rigid connection between the foot and pedal to allow the gradual depression of the pedal, but that should pressure be suddenly applied as under the uncontrollable depression of the foot when the car is traversing rough roads, the member 20 will yield or collapse sufficiently to prevent the unintentional depression of the pedal.

It is to be noted that because of the fact that the body 20 is formed of rubber or other heat insulating material, the transmission of heat from the accelerator pedal to the foot of the operator is prevented, thereby eliminating the burning sensation experienced in making trips of long duration. Further, the fact that the member 20 is formed of relatively soft material, a

cushion is provided between the accelerator pedal and the foot which prevents the formation of callous spots upon the foot of the operator.

5. Although I have herein shown and described only one form of accelerator pedal attachment embodying my invention, it is to be understood that various changes and modifications may be made herein without departing from the spirit of the invention and the spirit and scope of the appended claims.

What I claim is:

1. In combination, an accelerator pedal for internal combustion engines, and a body on the pedal sufficiently rigid to allow the gradual application of foot pressure in depressing the pedal, which collapses or yields when subjected to sudden pressure, thereby preventing the transmission of such sudden pressure to the pedal.

2. An attachment for accelerator pedals comprising a hollow resilient body.

3. An attachment for accelerator pedals comprising a hollow body formed of rubber.

4. An attachment for accelerator pedals comprising a hollow body formed of rubber and provided with a port through which air may move inwardly or outwardly of the body.

5. An attachment for accelerator pedals comprising a collapsible body constructed to withstand, without collapsing, a predetermined pressure gradually applied.

6. An attachment for accelerator pedals comprising a flanged supporting member, means for attaching the member to a pedal, and a hollow resilient body confined on the member and having a bleeding port.

7. An attachment for accelerator pedals

comprising a semi-spherical hollow body formed of rubber and provided with a port.

8. An attachment for accelerator pedals comprising a supporting plate, a flange on the plate, bendable fingers secured to the plate, and a hollow resilient body confined on the plate by said flange and having a port therein.

9. An attachment for accelerator pedals comprising a resilient member adapted to collapse when subjected to sudden pressure.

10. An attachment for accelerator pedals comprising a pneumatic member adapted to provide a yieldable support for the foot, for the purpose described.

11. An attachment for accelerator pedals comprising a hollow body formed of resilient material and provided with a vent through which air may move inwardly or outwardly of the body.

12. In combination, an accelerator pedal and a body on the pedal sufficiently rigid to allow the gradual application of foot pressure in depressing the pedal, which collapses or yields when subjected to sudden pressure, thereby preventing the transmission of such sudden pressure to the pedal.

13. An attachment for accelerator pedals comprising a body sufficiently rigid to allow the gradual application of pressure in depressing the pedal but which yields when subjected to sudden pressure to prevent the transmission of such sudden pressure to the pedal.

14. An attachment for accelerator pedals as embodied in claim 14, wherein a member confines the body on the pedal and bendable means secures the member to the pedal.

JAMES M. BRENNAN.
